METHOD AND APPARATUS FOR COATING

Raymond J. Wean, Warren, Ohio, assignor to The
Wean Engineering Company, Inc., Warren,
Ohio, a corporation of Ohio

Application December 21, 1935, Serial No. 55,597

1 Claim. (Cl. 91—12.7)

This invention relates to the art of coating and in particular to the maintenance of a clean surface on a bath of coating fluid. The invention pertains specifically to the tinning of sheet steel and will be described with reference thereto although it has other applications as well.

Tinning of steel sheets is usually carried on by passing the sheets longitudinally through a so-called tin-pot in which a bath of molten tin is maintained in a fluid condition. During the progress of the operation, floating accumulations known as scruff form on the surface of the tin bath. This scruff is apt to adhere to the sheet metal passing through the bath, and mar the surface finish thereof.

It is an object of my invention, therefore, to provide a method and apparatus for removing the scruff from the surface of the bath to prevent such marring of the sheets. I also make arrangements for the collections of the scruff at one side of the bath for easy removal therefrom.

In accordance with my invention, I provide a screw conveyor extending across the bath and having spiral flights thereon projecting down into the tin. The conveyor is driven by any convenient means and is effective to move the scruff on the surface of the tin toward the side of the bath in a direction transverse to that in which the material moves therethrough.

The invention will be more completely described with reference to the accompanying drawings and the novel features thereof pointed out in the appended claim.

In the drawings:

Figure 1 is a central longitudinal sectional view taken through a tin-pot having the apparatus of the invention incorporated therein;

Fig. 2 is a sectional view along the line II—II of Fig. 1; and

Fig. 3 is an enlarged view of a portion of the screw conveyor.

Referring now in detail to the drawings, a tin-pot 10 is substantially of conventional form except for the invention to be described and comprises a container 11 with entering feed rolls 12 suitably journaled therein at one end and exit rolls 13 similarly positioned at the other end. The entering feed rolls 12 are mounted in a frame composed of side plates 14 connected by cross members 15. The exit rolls 13 are similarly journaled in a frame 16. A curved guide 17 is effective to direct sheets from the feed rolls to the exit rolls.

The container 11 includes a well 18 for the molten tin and a chamber 19 for a layer of palm

oil which floats on the tin and through which the coated sheets pass after leaving the tin bath. The level of the tin at the exit end of the pot is shown at 20 and the level of the palm oil thereabove is indicated at 21. At the entering end of the pot, the level of the tin is indicated at 22. A layer of molten flux floats thereabove. Immersion heaters 23 are mounted adjacent the entering end of the pot to heat the contents thereof.

The path of a sheet through the pot is indicated by the line 24. In order to maintain a clean surface on the tin bath adjacent the point at which the material enters the tin, I provide a screw conveyor 25 journaled in the side plates 14. The conveyor is arranged to be driven by any convenient means, for example, the same drive which operates the feed-in and exit rolls 12 and 13. The conveyor 25 has spiral flights 26 thereon. As shown in Fig. 3 the flights are dished in the direction in which it is desired that the scruff be moved. The flights may all be of the same pitch or the flights on opposite sides of the center of the conveyor may be of opposite pitch, as shown in Fig. 2, whereby to cause movement of the scruff from substantially the middle of the bath toward the sides thereof. Scruff boxes 27 are disposed between the side plates 14 and the side walls of a container 11 adjacent the ends of the conveyor 25. The latter thus delivers scruff to the boxes 27 from which it may be easily removed.

If desired, a second conveyor 28 similar to that shown at 25 may be mounted as shown, on the opposite side of the path of the material traversing the pot. By this means a clean surface is assured throughout a fairly wide zone adjacent the point at which the material enters the bath. The conveyors 25 and 28 are preferably driven in opposite directions as indicated by the arrows in Fig. 2.

In operation, the screw conveyors serve to move all scruff or other floating accumulations toward the side of the bath and thus maintain a clean space therebetween for the entry of the material being coated. The conveyors also serve to circulate the flux floating on the entering side of the bath so that fresh flux is presented to the incoming material at all times.

The advantages of the method and apparatus described, in effecting a thorough cleaning of the surface of the bath adjacent the point of entry of material thereinto, will be readily appreciated. Adherence of the scruff to the material is prevented so that a larger percentage of the tinned sheets have a perfect surface. The invention involves only a slight change in the mechan-

ical structure of the tin-pot and can, therefore, be adopted at relatively little cost. The added parts are very few and there is substantially no increase in the maintenance cost of the apparatus.

It will be understood that while I have illustrated and described herein but one preferred practice of my invention, changes therein may be made within the spirit of the invention and the 10 scope of the appended claim.

What I claim is:

In a coating apparatus including a container for a fluid coating material, means for removing floating accumulations from the surface of said material comprising a screw conveyor having its axis substantially parallel to said surface and helical flights extending into said surface, and a scruff box adjacent one end of the conveyor, the conveyor being effective to feed said accumulations into said scruff box.

RAYMOND J. WEAN.
